UNITED STATES PATENT OFFICE

MAURICE MARKS, OF NEW YORK, N. Y.

DESIGN FOR A TOILET ACCESSORY CONTAINER

Application filed April 11, 1933. Serial No. 47,753. Term of patent 14 years.

To all whom it may concern:

Be it known that I, MAURICE MARKS, a citizen of the United States of America, residing at New York city, county of New York, borough of Manhattan, and State of New York, have invented a new, original, and ornamental Design for a Toilet Accessory Container, of which the following is a specification, reference being had to the accompanying drawing, forming part thereof.

I claim:

The ornamental design for a toilet accessory container as shown.

MAURICE MARKS.
